UNITED STATES PATENT OFFICE

167,781

COMBINED DISPLAYING AND DISPENSING STAND

John R. Warp, Chicago, Ill., assignor to Flex-O-Glass, Inc., Chicago, Ill., a corporation of Illinois

Application June 28, 1950, Serial No. 10,797

Term of patent 14 years

(Cl. D80—10)

To all whom it may concern:

Be it known that I, John R. Warp, a citizen of the United States, residing at Chicago, in the county of Cook, and State of Illinois, have invented a new, original, and ornamental Design for a Combined Displaying and Dispensing Stand, of which the following is a specification, reference being had to the accompanying drawing, forming a part hereof.

In the drawing:

Fig. 1 is a perspective view of a combined displaying and dispensing stand embodying my new design.

Fig. 2 is a front elevational view of the stand of Fig. 1.

Fig. 3 is a right-hand end elevational view of the stand in Fig. 1.

I claim:

The ornamental design for a combined displaying and dispensing stand, as shown.

JOHN R. WARP.
